UNITED STATES PATENT OFFICE

130,202

DESIGN FOR A CAMERA

Joseph Mihalyi, Rochester, N. Y., and Walter D. Teague, Annandale, N. J.

Application September 23, 1941, Serial No. 103,460

Term of patent 14 years

To all whom it may concern:

Be it known that we, Joseph Mihalyi and Walter D. Teague, citizens of the United States of America, residing in Rochester, county of Monroe, State of New York, and in Annandale, in the county of Hunterdon, State of New Jersey, respectively, have invented a new, original, and ornamental Design for Cameras, of which the following is a specification, reference being had to the accompanying drawings, forming a part thereof, in which—

Fig. 1 is a perspective view taken from the front and side of a camera showing our new design with the front of the camera extended into a picture-taking position;

Fig. 2 is a perspective view taken from the back and side of the camera shown in Fig. 1;

Fig. 3 is a top plan view of the camera shown in the preceding figures with the front of the camera extended into a picture-taking position; and

Fig. 4 is a bottom plan view of the camera shown in the preceding figures, but with the camera parts in a folded position.

We claim:

The ornamental design for a camera, as shown and described.

JOSEPH MIHALYI.
WALTER D. TEAGUE.
